(57) CLAIM

The ornamental design for a bottle, as shown and described.

DESCRIPTION

FIG. 1 is an isometric view of a bottle showing our new design;
FIG. 2 is a left view thereof;
FIG. 3 is a right thereof;

FIG. 4 is a front view thereof;

FIG. 5 is a back view thereof;

FIG. 6 is a top view thereof; and,

FIG. 7 is a bottom view thereof.

In the drawings, the broken lines in FIGS. 1-7 depict portions of the design that form no part of the claim.
